The ornamental design for a balance of plant online rack and module assembly, as shown and described.

DESCRIPTION

FIG. 1 is a perspective view of a balance of plant online rack and module assembly, showing the new design.

FIG. 2 is a front-side view thereof.

FIG. 3 is a back-side view thereof.

FIG. 4 is a top-side view thereof.

FIG. 5 is a bottom-side view thereof.

FIG. 6 is a right-side view thereof; and,

FIG. 7 is a left-side view thereof.

The broken line portion of the figure drawings is included to show unclaimed subject matter only and forms no part of the claimed design.
